Primary Examiner—Cathron C. Brooks*(74) Attorney, Agent, or Firm*—Womble Carlyle Sandridge & Rice**(57) CLAIM**

The ornamental design for a “drawer panel,” as shown and described.

DESCRIPTION

FIG. 1 is a perspective view of a drawer panel showing my new design with a drawer shown in phantom lines to provide context; and,

FIG. 2 is a top plan view thereof.

The broken lines shown are for illustrative purposes only and form no part of the claimed design.
